UNITED STATES PATENT OFFICE

LEOPOLD KAHN, OF MANNHEIM, GERMANY, ASSIGNOR TO PAUL PETER MUELHENS, DOING BUSINESS AS EAU DE COLOGNE- & PARFÜMERIE-FABRIK "GLOCKENGASSE NO. 4711" GEGENÜBER DER PFERDEPOST VON FERD. MÜLHENS, OF COLOGNE-ON-THE-RHINE, GERMANY

NONREFILLABLE CONTAINER FOR POWDER

Application filed February 3, 1932, Serial No. 590,625, and in Germany September 9, 1931.

This invention relates to a novel and improved non-refillable replacement container for face powder and the like and its object is to prevent such replacement containers being fraudulently refilled with face powder or other like material of another make than that which the purchaser believes he or she is buying. Such replacement containers are generally held in a more permanent and decorative metal case having a hinged lid and in addition to the replacement container this metal box usually holds the powder puff and may have a small mirror on the inner face of the lid. The present invention applies solely to the replacement container which is purchasable as a separate article and when the powder has all been used it is replaced by another.

According to this invention the powder is held in a receptacle suitably hollowed out and a flexible sieve of fine mesh is laid over the powder and retained in position by means of a retaining band embracing the sides of the receptacle and having an inwardly projecting flange extending over the edge of the sieve to retain it in place. As the powder is used the flexible sieve conforms to the top surface of the powder. It is sometimes preferred to employ a sieve which is not only flexible but is elastic. The invention will be more readily understood from the following description made with reference to the accompanying drawing and the novel features thereof are set forth in the claim.

Referring to the drawing:—

Figure 1 is a plan view looking down on an open metal box with a replacement powder container in accordance with this invention inserted therein.

Figure 2 is a section on the line 2—2 of Figure 1.

The powder is contained in the hollowed out top of the receptacle *a* which is so shaped as regards its hollowed out portion that a flexible material such as a metallic sieve of fine mesh or a fabric can fully conform to such internal surface without leaving any unfilled corners. Such a shape is obtained when the receptacle *a* has in cross section the plano-concave form shown in Figure 2. The

hollowed out portion thus has a plano-convex formation the plane surface of which forms the top of the receptacle. Around the border of this plano-convex cavity there is left a flat rim on which the edges of a sieve *b* of fine mesh can rest. There is preferably a cover piece, which may be made of a stout paper and is indicated by the reference letter *c*. This cover *c* may surround the base and sides of the receptacle *a* and is conveniently provided with an in-turned flange at *c'* and it is on this flange that the sieve rests. In charging the receptacle or container with face powder or the like, the powder is inserted in the hollowed out cavity of the receptacle after the covering *c* with its in-turned flange *c'* is in place. The sieve of suitable flexible material, such as a fine meshed metal sieve, is then laid in position. A retaining band or rim *d* is then laid around the receptacle and cover, being suitably attached as by an adhesive. The retaining band *d* has an inturned flange *d'* at its upper edge and this in-turned flange passes over the edge of the sieve *b* and retains it in place, even when the sieve in use is flexed downwardly, as for instance as shown by the dotted position indicated at *b'* in Figure 2. If the sieve is made of metal wire, which is flexible but not very elastic, the flange or rim *d'* and the inturned flange *c'* allow the edge of the sieve to slide a small amount when it is flexed and the amount of this sliding movement permits the metal sieve to conform to the convexity of the bottom of the hollowed out receptacle. The retaining band *d* may also have an inwardly projecting flange *d''* at its base or bottom of the receptacle. The entire replacement container, is held in the metal box *e* which has a hinged lid *f*.

In use powder puff is pressed on to the top of the sieve which causes a small amount of powder to pass through the mesh. As the powder passes through the mesh of the sieve the sieve retains the formation of the top surface of the powder. This continues until all the powder has been passed through the mesh and the sieve then lies close against the bottom of the cavity of the receptacle. It is in practice impossible to refill such a contain-

er without destroying most of the component parts. If the sieve is made of a flexible and elastic fabric, such as silk, the edges of the sieve may be firmly held between the inwardly turned flanges c' and d' .

5 I claim:

A non-refillable face powder container comprising a receptacle hollowed out to contain powder, a cover piece around said receptacle and having an inturned top flange bordering said hollowed out part of the receptacle, a flexible sieve resting on said inturned flange, a retaining band around said cover, an inturned flange on the upper end of said 10 retaining band and extending over the border of the sieve to retain the same in place during use and an inturned flange on the lower part of said retaining band and embracing the bottom of the cover piece.

15 20 In testimony whereof I affix my signature.

LEOPOLD KAHN.
